THEODORE HEISS, OF BALDWIN, MICHIGAN.

TRAP AND SUBMARINE-MINE CONSTRUCTION.

1,280,026.

Specification of Letters Patent. Patented Sept. 24, 1918.

Application filed June 25, 1917. Serial No. 176,741.

To all whom it may concern:

Be it known that I, THEODORE HEISS, a citizen of the United States, residing at Baldwin, Lake county, Michigan, have invented certain new and useful Improvements in Trap and Submarine-Mine Construction, of which the following is a specification.

This invention relates to an improved trap and submarine mine construction.

The objects of the invention are:

First, to provide an improved mine structure which will have a large radius of action for the destruction of submarines.

Second, to provide such a structure which is very light, simple and inexpensive to construct.

Third, to provide such a structure which is easy to place in position for its work.

Fourth, to provide such submarine mine so constructed that it does not affect the safety of navigation at the surface.

Further objects and objects relating to details of construction and operation will definitely appear from the detailed description to follow.

I accomplish the objects of my invention by the devices and means described in the following specification. The invention is clearly defined in the claims. A structure embodying a preferred form of my invention is clearly illustrated in the accompanying drawing, forming a part of this specification, in which:

Figure I is a detail elevation view of a structure embodying the features of my invention.

Fig. II is an enlarged detail view of the mine part and its connections to the outer rim for supporting the same.

Fig. III is an enlarged detail view of the mine part and the connections for tripping the same.

Fig. IV is an enlarged detail edge elevation view of the parts appearing in Fig. II, showing the relation of the mine support and the connections for tripping the same.

In the drawings similar numerals of reference refer to similar parts throughout the several views.

The structure comprises a supporting rim 1, preferably of about one-fourth inch rod, and in the structure illustrated, for example, this is in the form of a ring of about ninety-six feet in diameter. The dimensions of the ring will vary according to the depth of the

water to be mined and should be of such dimension that it will reach from the bottom to within safe distance from the top for the passage of vessels on the surface; 60 say, for instance, a distance of within twenty-five or thirty feet beneath the surface.

Radial rods 2 extend from this ring to the center and support a flat disk-like mine 3 containing the charge, the rods 2 being 65 connected thereto by clip pieces 4, or in any other desired manner. Contact firing pins 5 are provided for the mine.

A disk-like anchor weight 6 is to hold the lower side of the rim against the bottom, 70 the same being secured to the rim and vertical radial rod 2 by ties 7 or by any other suitable means. A stiffener 6^a is also secured to the bottom side.

A float 9 which may be of a strip of cork 75 or a pneumatic tube or any other suitable device, is secured to the top side of the rim and opposite the weight 6, to carry the upper side of the rim up toward the surface. The float is sufficient to hold the structure 80 in vertical position in the water but not sufficient to raise the weight 6 above the bottom.

A time fuse is provided to which are connected radial rods 11 which are secured at 85 their outer ends to a ring 12 which is in spaced relation to the mine 3, so as to permit freedom of movement of the ring in all directions for tripping the time fuse. The ring 12 is connected to the rim 1 by trip 90 loops 13, the same being secured to the rim by clip wires 14 suitably spaced, and at their inner ends they are secured by suitable connecting means 15 to the ring 12 of the tripping means for the time fuse. Sliding connections 16 couple the adjacent trip loops 13, whereby they are retained in position in disk-like relation around the mine within the outer rim 1. These loops are of such form and dimensions as to permit the free 100 passage of silt, seaweed, drift and similar ocean waste.

I have described and illustrated the structure as about ninety-six feet in diameter. It is clear that it is practical to make the same 105 of much larger diameter and also that the same will be effective if of lesser diameter where the water is shallower, depending on the depth of the ocean bed or channel which is being mined.

The weight 6 for anchoring is made a flat disk so that it will serve as a rudder to swing

the structure with the ebb and flow of the tide, and that is also the purpose of making the mine in flat disk form. The mine is made of such weight as to substantially 5 float and maintain its position above the weight but not sufficient to overcome the anchorage. The stiffener 6^a may be omitted but is of advantage in keeping the rim distended.

10 In operation when the mine is in position, the nose of an advancing submarine, if it comes within the outer rim, must, as it proceeds, pull upon one or another of the trip loops 13, which by its connection at once 15 trips the time fuse 10 and sets it in operation. As the submarine advances, owing to the fact that the mine structure is very light, it will raise it from the bottom and the flat disk-like mine and the disk-like anchor, 20 owing to the manner in which they are secured in place, at once serve as rudders and guide the mine into contact with or in close relation to the side of the advancing submarine, no matter at what point or what position 25 it has engaged the device. So that if the vessel comes either to the right side or the left side of the mine, the mine will swing against the side of the vessel; and if the nose of the vessel passes above the mine, the 30 mine will swing up against the bottom; and if the nose of the vessel passes at a point below the mine, the mine will be swung down onto the deck.

35 This swinging motion is sufficient to actuate a contact firing pin and therefore I have provided such, indicated at 5 on the mine, but the safest method is the time fuse, which will be tripped as the vessel is advancing and insures the explosion even though the 40 mine does not fully contact. The structure is much more certain in its action by operating with the time fuse, but it will be very effective if operated by the contact firing pin.

45 I have shown the structure in the form preferred by me, but it is very clear that any mesh work disposed within the outer rim and connected to the time fuse would operate quite effectively, although the particular arrangement that I have referred to possesses merits in the particulars I have indicated.

55 The matter of dimension is controlled by the circumstances under which the device is to be used. The loops 13 may have a width, and in fact preferably have a width, of about fifteen feet, this being sufficiently small not to pass over the driving rudders of a submarine and at the same time practically insuring the passage of the nose of a submarine well through the structure to insure its 60 most effective action. The structure practically will not be engaged or acted upon by the usual mine sweeping devices, and if it did become engaged, it would simply explode and not fall into the hands of an

enemy. It will be seen from this explanation that a ship passing above and coming in contact with the outside of the rim 1 will pass without operating the device, and in the event the propeller should accidentally 70 engage the same and become entangled the explosion would occur at such a distance back of the vessel that it would be harmless. The depth at which the structure is used and the form of it will make this accident well 75 nigh impossible but it will be observed that such is fully provided for.

Having thus described my invention, what I claim as new and desire to secure by Letters Patent is:

1. In a submarine mine structure, the combination of a metallic rim anchored with a disk-shaped weight and a stiffener at the bottom, with a suitable float at the top, a centrally disposed disk-shaped mine, a time 85 fuse therefor, contact firing pins on the sides of said mine, radial cross rod supports for said mine for maintaining the mine in position, radially disposed trip loops in sliding engagement with each other, secured to said rim, a central connection ring for the said trip loops, and connections therefrom to the time fuse, coacting for the purpose specified. 90

2. In a submarine mine structure, the combination of a metallic rim anchored with a disk-shaped weight and a stiffener at the bottom, with suitable float at the top, a centrally disposed disk-shaped mine, a time fuse 95 therefor, radial cross rod supports for said mine for maintaining the mine in position, radially disposed trip loops in sliding engagement with each other, secured to said rim, a central connection ring for the said trip loops, and connections therefrom to the time fuse, coacting for the purpose specified. 100

3. In a submarine mine structure, the combination of a metallic rim anchored with a disk-shaped weight and a stiffener at the bottom, with suitable float at the top, a centrally disposed disk-shaped mine, a time fuse 110 therefor, radial cross rod supports for said mine for maintaining the mine in position, radially disposed trip loops secured to said rim, a central connection ring for the said trip loops, and connections therefrom to the time fuse, coacting for the purpose specified. 115

4. In a submarine mine structure, the combination of a metallic rim anchored with a weight at the bottom, with suitable float at the top, a centrally disposed mine, a time 120 fuse therefor, radial cross rod supports for said mine for maintaining the mine in position, radially disposed trip loops secured to said rim, a central connection for the said trip loops, and connections therefrom to the time fuse, coacting for the purpose specified. 125

5. In a submarine mine structure, the combination of a metallic rim with an anchor at the bottom and a suitable float at the top, a centrally disposed disk-shaped mine con- 130

nected to and supported by the said rim, a time fuse for said mine, contact firing pins, a loop structure disposed within the said rim and connected to the said time fuse 5 adapted to operate the said fuse by contact of a moving submarine, the structure being adapted to fold about the body of the submarine and bring the mine into position to act on the same, coacting for the purpose 10 specified.

6. In a submarine mine structure, the combination of a metallic rim with an anchor at the bottom and a suitable float at the top, a centrally disposed mine connected to and 15 supported by the said rim, a time fuse for said mine, contact firing pins, a loop structure disposed within the said rim and connected to the said time fuse adapted to operate the said fuse by contact of a moving 20 submarine, the structure being adapted to fold about the body of the submarine and bring the mine into position to act on the same, coacting for the purpose specified.

7. In a submarine mine structure, the combination of a metallic rim with an anchor at 25 the bottom and a suitable float at the top, a

centrally disposed mine connected to and supported by the said rim, contact firing pins, a loop structure disposed within the said rim, the structure being adapted to fold 30 about the body of the submarine and bring the mine into position to act on the same, coacting for the purpose specified.

8. In a submarine mine structure, the combination of a metallic rim with an anchor at 35 the bottom and a suitable float at the top, a centrally disposed mine connected to and supported by the said rim, a time fuse for said mine, a loop structure disposed within the said rim and connected to the said time fuse 40 adapted to operate the said fuse by contact of a moving submarine, the structure being adapted to fold about the body of the submarine and bring the mine into contact with the same, coacting for the purpose specified. 45

In witness whereof, I have hereunto set my hand and seal in the presence of two witnesses.
